FIG. 1.

FIG. 2.

INVENTOR
Edwin C. Larry

BY
Lyman E. Dodge
ATTORNEY

UNITED STATES PATENT OFFICE.

EDWIN C. LARRY, OF ROCHESTER, NEW YORK, ASSIGNOR TO GENERAL RAILWAY SIGNAL COMPANY, OF GATES, NEW YORK, A CORPORATION OF NEW YORK.

SWITCH-THROW-ROD CONNECTION.

1,159,319.

Specification of Letters Patent.

Patented Nov. 2, 1915.

Application filed May 18, 1915. Serial No. 28,865.

To all whom it may concern:

Be it known that I, EDWIN C. LARRY, a citizen of the United States, and a resident of the city of Rochester, in the county of Monroe and State of New York, have invented a new and useful Switch-Throw-Rod Connection, of which the following is a specification.

This invention relates to a switch-throw-rod connection and has for its object to provide an efficient and inexpensive connection of this class which is readily adjustable to accommodate any difference in range of movement of the rod operating lever or machine relatively to the required extent of movement of the switch point, and to permit every necessary freedom of lateral movement of the throw rod in the connection casing to avoid sticking or binding of the rod under any condition of use, and also to provide a throw-rod connection having few and simple parts which in operation practically clear themselves of dust, dirt or moisture.

Other objects and advantages will appear as the description of the invention progresses, and the novel features of the invention will be particularly pointed out in the appended claims.

Reference is made to the accompanying drawings forming part of this specification, and in which:

Figure 1 is a detail plan view of a short length of railway track and adjustable switch points thereat coupled to the switch throw-rod by this improved connection.

Fig. 2, is an enlarged somewhat broken plan view, partly in horizontal section on the line *a—a*, in Fig. 3, and Fig. 3, is a central transverse vertical section taken on the line *b—b*, in Fig. 2, and also shows the switch point tie-bar in dotted lines.

The numerals 1, 1, indicate short sections of rails of a railway track, and 2, 2, indicate the points of two switch rails rigidly connected by a lengthwise adjustable front rod 3, and suitable tie-bars, but one tie-bar 4, being shown and to which is fastened the improved throw-rod connection generally indicated in Fig. 1 by the letter A, and which now will be described with more special reference to Figs. 2 and 3 of the drawings.

The numeral 5, indicates the connection casing which preferably is a single metal casting having a laterally extending top

flange 6, provided with holes 7, through which pass bolts 8, rigidly fastening the casing to the tie-bar 4, in manner shown in Fig. 1 of the drawings. The main body portion of the casing 5, has general cylindrical form and its central interior part is provided with a series of inwardly projecting ribs 9, separated at the ends by spaces of which there preferably are four constituting dust and dirt clearance channels 10, the bottom one of which is extended through the wall of the casing at 11, to provide for free gravitational discharge of dust and dirt and moisture from the inner central part of the casing. The ribs 9, together form an abutment against opposite faces of which the inner ends of two hollow and generally cylindrical nuts 12, 13, may stop. These nuts are fitted at their outer end portions upon a screwthread 14 formed on the end part of the switch throw-rod 15, and lock nuts 16, 16, on this rod provide for securing the nuts 12, 13, against longitudinal movement after they are once properly adjusted on the rod to provide necessary movement clearance relatively to the abutment 9, to accommodate the switch rails and the lever or machine operating the switch. The inner ends of the nuts 12, 13, are cored or bored so as to move freely over the rod threads 14, and this core or bore extends outwardly for most of the length of the nuts or up to their outer internally threaded end portions which move on the throw-rod threads 14, and thus the cylindrical or barrel-shaped nuts provide a dust and weather guard for the screwthreads of the throw-rod. Fig. 3 more clearly shows that the two nuts 12, 13, normally rest directly upon the bottoms of the two respective casing chambers 17, 18, at opposite sides of the rib abutment 9, through which the throw-rod 15, freely passes, and whereby the utmost freedom of lateral movement of the rod and its two nuts 12, 13, is permitted and also assures that when the rod and nuts are moved endwise to close or open the switch, the nuts more effectually force possible dust and dirt accumulations from the casing chambers 17, 18, and particularly at or through the lower central discharge opening 11, of the casing. The few, simple, inexpensive and durable parts of this switch throw-rod connection thus are practically self-clearing as regards dust and dirt and the bottom

casing opening 11, provides free and ample drainage for moisture entering the casing. The nuts 12, 13, with their lock nuts 16, are a preferred means adjustable on the throw-rod 15, for offering resistance at the abutment for properly limiting endwise movements of the rod in the connection casing.

Although I have particularly described the construction of one physical embodiment of 10 my invention, and explained the operation and principle thereof; nevertheless, I desire to have it understood that the form selected is merely illustrative, but does not exhaust the possible physical embodiments of the 15 idea of means underlying my invention.

What I claim as new and desire to secure by Letters Patent of the United States, is:

1. A switch throw-rod connection comprising a casing, a throw-rod entering the 20 casing, an abutment in the casing through which the rod freely passes, and two adjustable pressure resistance means on the rod one at each side of the abutment and having movement clearance relatively thereto and normally resting on the bottoms of 25 the casing chambers which contain them, said casing having a bottom dust and dirt and moisture clearance opening at the abutment.
- 30 2. A switch throw-rod connection comprising a casing, a screwthreaded throw-rod entering the casing, an abutment in the casing through which the rod freely passes, and two nuts on the rod one at each side of the abutment and having movement clearance relatively thereto and normally resting on the bottoms of 35 the casing chambers which contain them, said casing having a

bottom dust and dirt and moisture clearance opening at the abutment.

3. A switch throw-rod connection comprising a casing, a throw-rod entering the casing, an abutment in the casing through which the rod freely passes, and having a plurality of longitudinal dust and dirt 45 clearance channels one of which is extended outward for drainage through the bottom wall of the casing, and two adjustable pressure resisting means on the rod one at each side of the abutment and having movement 50 clearance relatively thereto.

4. A switch throw-rod connection comprising a casing, a screwthreaded throw-rod entering the casing, an abutment in the casing through which the rod freely passes and having a plurality of longitudinal dust and dirt clearance channels one of which is extended outward for drainage through the bottom wall of the casing, and two nuts on the rod one at each side of the abutment 55 and having movement clearance relatively thereto.

5. A switch throw-rod connection comprising a casing, a screwthreaded throw-rod entering the casing, an abutment in the casing through which the rod freely passes and having a plurality of longitudinal dust and dirt clearance channels one of which is extended outward for drainage through the bottom wall of the casing, and two nuts on the rod one at each side of the abutment and having movement clearance relatively thereto and normally resting on the bottom of 70 the casing chambers which contain them.

EDWIN C. LARRY.
